UNITED STATES PATENT OFFICE.

FRANK H. HAMBLIN, OF WORCESTER, MASSACHUSETTS.

DESIGN FOR A PLATE-LIFTER.

SPECIFICATION forming part of Design No. 28,220, dated January 25, 1898.

Application filed July 26, 1897. Serial No. 646,044. Term of patent 14 years.

To all whom it may concern:

Be it known that I, FRANK H. HAMBLIN, a citizen of the United States, residing at Worcester, in the county of Worcester and State of Massachusetts, have invented a new and useful Design for Plate-Lifters, of which the following is a specification, reference being had to the accompanying drawing, which shows a perspective view of a plate-lifter embodying my design.

My design for plate-lifters is characterized by a twisted body portion A, comprising two strands contrasting in color, which strands extend from the body portion A to form feet or socket-pieces B.

I am aware of United States Design Patent No. 22,534, granted June 13, 1893, to William T. Russell, which shows a design for plate-lifters having a body portion comprising

ing two main wires twisted together with a smaller braided wire, and disclaim such design, as the body portion of my design comprises simply two strands contrasting in color and of substantially the same size twisted together.

Having thus fully described my design, what I claim as new, and desire to secure by Letters Patent of the United States, is—

The design for plate-lifters, substantially as shown and described.

In testimony whereof I have hereunto set my hand in the presence of two subscribing witnesses.

FRANK H. HAMBLIN.
